WALL CABINET

Filed March 11, 1929

Inventor:
August J. Smith.

Charles J. Smith.

July:

UNITED STATES PATENT OFFICE

AUGUST J. SMITH, OF CHICAGO, ILLINOIS

WALL CABINET

Application filed March 11, 1929. Serial No. 345,974.

In the construction of wall cabinets such as medicine cabinets and the like it has been the practice to equip the door of the cabinet with a mirror which is either mounted within a frame forming a part of the door or is attached to the front surface of the door by means of glass screw bolts or the like thereby requiring the services of one or two glaziers to properly perform the work entailed in placing the mirror in position. In Venetian design cabinets which are equipped with fancy mirrors the expense for mounting each of the mirrors is a considerable item.

This invention relates to an improved open frame for the door of a medicine cabinet or the like with said frame so constructed that a finished fancy mirror may be conveniently slid into place through the upper end of the open frame and securely held in place in the cabinet door without requiring the services of a glazier.

It is an object of this invention to provide a wall cabinet having a door provided with a three-sided frame adapted to permit a mirror to be slidably engaged in the frame through the upper portion of the door.

It is also an object of this invention to provide a wall cabinet with a door having an open frame to permit a mirror to be conveniently and rapidly mounted in position on the door without requiring the services of an expert.

It is an important object of this invention to provide a wall cabinet having a door provided with grooved parallel guide members to permit a mirror to be slidably mounted in position after the wall cabinet has been installed.

Other and further important objects will be apparent from the disclosures in the specification and the drawings.

This invention (in a preferred form) is illustrated in the drawings and hereinafter more fully described.

On the drawings:

Figure 1 illustrates a fragmentary portion of a wall having mounted in a recess thereof a wall cabinet provided with a mirrored door embodying the principles of this invention.

Figure 2 is an enlarged transverse section taken through the wall cabinet on line II-II of Fig. 1 and illustrating the open position of the door in dotted lines.

Figure 3 is a central vertical longitudinal section of the wall cabinet taken on line III-III of Fig. 2.

As shown on the drawings:

The reference numeral 1 indicates a wall having a recess therein in which an improved medicine or wall cabinet is adapted to be mounted. The wall cabinet comprises a casing 2 constructed of metal or other suitable material. The casing 2 is open at the front and is provided with a channel flange frame 3 which is adapted to seat against the surface of the wall 1 when the casing 2 is properly seated in position.

The casing 2 is provided with a plurality of removable shelves 4 which are adapted to be seated in place upon shelf supporting bars or brackets 5 secured in parallel relation on the inner surfaces of the side walls of the cabinet 2.

Pivotal to one of the side members of the casing frame 3 by means of hinges 6 is a metal door plate 7 which is reinforced on its back by means of a flanged channel shaped rib 8 the side flanges of which are brazed to the back of the door-plate. Rigidly secured to the lower margin or edge of the door-plate 7 is a channel cross-sectioned frame bar 9 the ends of which are mitered as indicated by the reference numeral 10 to permit the lower mitered ends of a pair of channel cross-sectioned side frame members 11 to be connected therewith. The frame side members 11 are rigidly secured by brazing or other suitable means to the longitudinal margin of the metal door plate 7. The upper ends of the frame side members 11 are capped by means of grooved heads or decorative finishing members 12. Rigidly secured to the under surface at one end of the lower frame cross-bar 9 is a lug or handle 13 to facilitate opening and closing of the wall cabinet door.

The three grooved or channel cross-sectioned frame members 9 and 11 are secured to the metal door plate 7 to afford a three-sided mirror receiving frame projecting beyond

the front or outer side of the door panel. Glued or otherwise secured to the front face of the door plate 7 is a layer of felt 15 or other suitable cushioning material adapted to form a suitable backing for a fancy plate mirror 14 which is adapted to be removably inserted into the open upper end of the frame side members 11 to permit the mirror to seat in the lower frame member 9 to entirely cover the front of the door-plate 7. The upper end of the mirror 14 may be straight or of any fanciful configuration depending upon the design of the mirror. The upper end of the door-plate 7 is shaped to correspond or register with the shape of the upper end of the mirror which is to be carried by the door.

From the description given it will be noted that the improved wall cabinet may be mounted in position without the mirror being in place, thereby eliminating any possibility of damage being done to the mirror during shipment or installation. After the cabinet has been mounted in a wall recess and the door is properly secured in place the mirror 14 may be conveniently slid downwardly into position in the frame side members 11 until the lower margin of the mirror seats within the lower frame member 9. The work of installing the mirrors after the cabinets have been mounted in place may be done by any person without requiring the services of a glazier or an expert workman.

Attention is directed to the fact that the improved narrow grooved frame 9-11 on the cabinet door is provided for the prevention of glass breakage during the shipment of cabinet having the mirror mounted in place. The grooved frame also affords protection for the mirror when a cabinet is in use, especially when the door is slammed. Breakage of the mirrors often occurs in cabinets having the mirrors mounted on metal or wood backs by means of ornamental rosettes and screws, due to the fact that the weight of the mirrors strain the screws causing cracks in the glass, which results are obviated by the use of the improved grooved open frames and the cushioned backs of the present invention.

I am aware that many details of construction may be varied through a wide range without departing from the principles of this invention and it is therefore not purposed, limiting the patent granted hereon otherwise than necessitated by the scope of the appended claim.

I claim as my invention:

In a wall cabinet having a casing for mounting in a recess in a wall of a room, a metal door plate hinged on the casing, and means on the door plate whereby a plate glass mirror may be slid into retained position on the door plate after the casing has been mounted in the wall, the said means including a three-sided frame of open-grooved

channel members secured along the lower and the vertical marginal portions of the door plate.

In testimony whereof I have hereunto subscribed my name at Mount Pleasant, Isabella County, Michigan.

AUGUST J. SMITH.
